MUTED AUTOMATIC VOLUME CONTROL

Jacob Yelles, Brooklyn, N. Y., assignor to Radio Corporation of America, a corporation of Delaware

Application October 26, 1933, Serial No. 695,238

5 Claims. (Cl. 250—20)

My present invention relates to automatic volume control arrangements of radio receivers, and more particularly to muter circuits for receivers employing automatic volume control networks. Modern broadcast radio receivers utilize automatic volume control arrangements in order to maintain the signal energy input to the demodulator of the receiver substantially constant regardless of received signal carrier amplitude variations. The employment of automatic volume control, however, gives rise to a serious source of annoyance when the signal carrier amplitude decreases below a predetermined intensity level. For example, when the signal carrier amplitude decreases to practically zero, the gain controlled amplifiers are at maximum sensitivity. This results in an excessive amplification of undesired electric background noise impulses. This amplification manifests itself as exceedingly annoying sounds in the loud speaker.

Various arrangements have heretofore been proposed to avoid the reproduction of such background noise impulses when the received signal carrier amplitude decreases below a predetermined intensity level. In the muters, or background noise suppressors, suggested heretofore at least one circuit in the receiver has been rendered inoperative to render inefficient the transmission of electric impulses to the reproducer. In order to impart a selective characteristic to the background noise suppressor arrangement, it has been shown by M. G. Nicholson, Jr., in application Serial No. 577,235, filed November 25th, 1931 that the input to the suppressor network should be tuned to the desired signal frequency.

It may be stated that it is one of the main objects of the present invention to provide an intercarrier noise suppressor arrangement for a radio receiver utilizing automatic volume control wherein the input circuit of the suppressor network is resonant to the desired signal frequency, and hence highly selective, the noise suppressor function being performed upon an audio amplifier which is disposed within the same tube envelope which houses the receiver detector.

Another important object of the invention is to minimize intercarrier noise in a receiver employing automatic volume control by means of a selective circuit, the muted tube being of the duplex diode triode type and embodying diode detector and audio amplification functions.

Another object of the invention is to provide a background noise suppressor system for a receiver utilizing automatic volume control, the

necessary negative cut-off bias for the noise suppression function being secured by means of a diode rectifier which is housed within the same tube envelope as an amplifier for the rectified signal voltage to be employed for the muting action.

Still other objects of the invention are to improve generally the efficiency of muting systems for receivers, and to particularly provide an interstation noise suppressor for a receiver employing automatic volume control which is not only reliable in operation, but readily assembled in a radio receiver.

The novel features which I believe to be characteristic of my invention are set forth in particularity in the appended claims. The invention itself, however, both as to its organization and method of operation, will best be understood by reference to the following description taken in connection with the drawing in which I have indicated diagrammatically several circuit organizations whereby my invention may be carried into effect.

In the drawings:

Fig. 1 diagrammatically shows a receiver employing one embodiment of the invention,

Fig. 2 diagrammatically shows a modified form of the invention.

Referring now to the accompanying drawings, wherein like reference characters in the two figures represent similar circuit elements, in Fig. 1 there is shown a radio receiver of a purely conventional type. Since superheterodyne receivers are most generally employed at the present time, the arrangement shown in Fig. 1 is of such a type. The numeral 1 designates a tunable radio frequency amplifier stage whose gain is to be automatically controlled. The numeral 2 designates the first detector, local oscillator and intermediate frequency amplifier stages of a superheterodyne receiver. It is not believed necessary to show the circuit details of the network 2, since those skilled in the art are well acquainted with such circuit design. It is merely necessary to point out that the tuned circuit 3 has impressed upon it the amplified signal which exists in the plate circuit of tube 1. The tuned coupling network 4 is maintained fixedly tuned to the operating intermediate frequency, which may be of the order of 175 kilocycles for example, and the intermediate frequency energy is impressed upon a second detector for demodulation.

The numeral 5 designates a type of tube known as a duplex diode triode, or a 55 tube. This is a multiple duty tube and performs simultaneously

second detection and audio frequency amplification functions. It additionally performs the automatic volume control function. The tube 5 is schematically shown since its specific construction has been disclosed and claimed by T. M. Shrader, in application Serial No. 622,140, filed July 12th, 1932. Further, the use of such a 55 type tube for the simultaneous three functions named has been disclosed and claimed by T. M. Shrader in the aforesaid application.

The second detector circuit consists of a half wave diode rectifier network including in series auxiliary anodes 6, tuned circuit 4', resistor 7 shunted by radio frequency by-pass condenser 8, and grounded cathode 9. The direct current component of the voltage developed across resistor 7 is used for automatic volume control, this function being provided by connecting the lead 9' including filter resistor 9'' (marked A. V. C.) between the grid circuits of the controlled tubes and the grid side of resistor 7. The audio component of rectified signal voltage is impressed on the grid 10 of the triode audio amplifier section of tube 5 through a path including direct current blocking condenser 11, adjustable tap 12 adapted to act as a manual volume control element, and resistor 13 connected between lead 9' and ground through condenser 14.

The plate 15 of tube 5 is coupled, as at M, to an audio frequency network which may comprise, one or more amplifier stages and/or a reproducer. Signal energy is also impressed upon a background noise suppressor network through a path which includes the condenser 16 and a signal selective network 17. The noise suppressor arrangement comprises a pair of tubes 18 and 19, the tube 18 functioning as a noise control tube. The variation of current flow in the plate circuit of rectifier tube 18 regulates the flow of current in the plate circuit of tube 19, and the variation in the current flow in the latter plate circuit regulates the transmission efficiency of the triode section of tube 55. The potentials required for the operation of tubes 18 and 19 are derived from a common bleeder which comprises resistor portions R₁, R₂, R₃, R₄, R₅ and R₆. The positive side of portion R₆ is grounded, and consequently is at the same ground potential as the cathode 9 of tube 5. The grounded side of portion R₆ is connected through further resistor portions to the positive terminal of the direct current supply source, and it is to be understood that this supply source may also provide the potentials for the remainder of the receiver tubes. A resistor R₇ is connected in shunt across portion R₁ between the negative terminal side of R₁ and the side thereof connected to the cathode of tube 18. The highly selective circuit 17, which is maintained fixedly tuned to the operating intermediate frequency, is connected between the signal grid of tube 18 and a desired point on resistor R₇ through a path which includes the resistor 20 and the adjustable tap 21, the tap side of resistor 20 being connected to ground through a by-pass condenser 22, and a condenser 23 connecting the cathode of tube 18 to the low potential side of the selective circuit 17. The cathode of tube 18 is connected to the junction of resistors R₁ and R₂, while the screen grid of tube 18 is connected to the junction of portions R₂ and R₃.

The cathode of tube 19 is connected to the junction of resistors R₃ and R₄, while the anode of tube 18 is connected to the signal grid of tube

19 through a resistor 24. A grid leak resistor 25 is connected between the anode side of resistor 24 and the cathode of tube 19, and the anode of tube 19 is connected to the signal grid 10 of tube 5 through a path which includes resistor 26 and lead 27. The anode of tube 19 is connected to the junction of resistor portions R₅ and R₆ through a resistor 28, and the screen grid of tube 19 is connected to the junctions of resistor portions R₄ and R₅.
10

The lead 27 is designated by the letters "N. S.", and it is to be clearly understood that this designates the background noise control path, or the intercarrier noise suppressor path. Merely by way of illustration, and not by way of restriction, or limitation, it is pointed out that the potential difference between the negative terminal of portion R₁ and the ground side of portion R₆ may be 211 volts, and the junction points between the resistor portions of the voltage supply 20 bleeder may have the following respective potential values: 37.5 volts; 44 volts; 121 volts; 161 volts; 203 volts. With regard to the regulated stages, and specifically amplifier tube 1, there may be employed a potential of about 400 volts 25 on the plate of tube 1, and in that case it will be noted that the grounded side of the cathode of tube 1 will be at a potential of 211 volts. For further specific illustration it is stated that the resistor R₁ may have a value of 500,000 ohms, the 30 resistor R₂ may have a value of 10,000 ohms; the grid leak resistor 25 and the resistor 28 may each have a value of $\frac{1}{4}$ of a megohm; the resistor 24 may have a value of $\frac{1}{2}$ of a megohm; and the resistor 26 may have a value of 1 35 megohm. Of course, it is quite obvious that any of these values given above may be changed to suit the particular requirements to which a broadcast receiver is to be put.

In actual operation, and with the tuning instrumentality 39 adjusted between station settings, normal transmission by the amplifier section of tube 5 is prevented. This transmission prevention function is secured by virtue of the fact that tube 19, with no signals passing through condenser 16, has sufficient potential drop across resistor 28 to bias the amplifier section of tube 5 to cut off. That is to say, the potential drop across resistor 28 adds to the normal negative bias obtained across resistor portion R₆, with no signals being collected, and cuts off the amplifier section of tube 5, thereby muting the receiver between desired station settings of the tuning device 30. This muting action is desirable, as is well known, because the AVC arrangement is 55 not effective at the no-signal condition of the receiver whereby the high frequency amplifiers are operating at maximum sensitivity. Undesired background noise impulses are greatly amplified when sensitivity is at its maximum, and 60 such undesired impulses are transmitted through the audio amplifier section of tube 5 and finally reproduced.

As soon as the signal energy above a predetermined intensity level is impressed upon the 65 selective circuit 17 the plate current flow of tube 18 increases, with the result that the signal grid of tube 19 has its negative bias increased to a point such that the tube 19 is biased to cut off. This means that the potential drop across resistor 28 decreases sufficiently to remove the cut off bias from the signal grid 10 of tube 5. This action effectively restores normal transmission through the audio amplifier section of tube 5. Of course, adjustment of tap 21 regulates the point 75

at which background noise suppression action will become effective.

In Fig. 2 is shown a simplified modification of the arrangement shown in Fig. 1. The audio amplifier section of tube 5 includes a screen grid electrode, and the audio component of the demodulated signal energy is derived from the resistor 7 which is arranged in series between the grounded cathode 9 and the low potential side of tuned circuit 4'. Otherwise the circuit involving tube 5 and its immediately associated circuits are exactly the same as shown in Fig. 1. The functions of the tubes 18 and 19 are performed simultaneously in Fig. 2 by the tube 31. This tube is of the same type as the tube 5 of Fig. 2, the signal rectification function of tube 18 being performed in Fig. 2 by the half wave diode rectifier circuit which includes in series the diode anodes 32, the selective circuit 17, the resistor 33 shunted by the radio frequency by-pass condenser, and the cathode of tube 31. The direct current component of the voltage developed across resistor 33 is impressed upon the signal grid of the amplifier section of tube 31 through a resistor 34. The bleeder of Fig. 1 is simplified in Fig. 2 to comprise four resistor portions R₈, R₄, R₅ and R₆. Otherwise the resistors employed in Fig. 2 whose numerals correspond to the numerals of the resistors in Fig. 1 function similarly. The background noise suppression path includes the lead 27 and resistor 26, and the potential drop across resistor 28 again regulates the transmission efficiency through the audio amplifier section of tube 5.

In operation, and with no signals being impressed upon the selective circuit 17, there is a maximum flow of current in the plate circuit of tube 31, and the potential drop across resistor 28 adds to the normal bias potential across resistor R₆ to bias the signal grid of tube 5 to cut off. Thus, normal transmission of signals through the audio amplifier section of tube 5 is prevented. When signal energy of sufficient amplitude is impressed upon selective circuit 17, there is a flow of rectified signal current through resistor 33, and the signal grid of the amplifier section of tube 31 is biased to a point such that the flow of current through resistor 28 sufficiently decreases to remove the signal grid of tube 5 from its cut off condition. Accordingly, it will be appreciated that in the arrangement shown in Fig. 2 a pair of multiple function tubes are utilized to perform signal demodulation, audio frequency amplification, automatic volume control, and muting functions simultaneously. It is pointed out that the condenser 16 loosely couples the primary circuit of the intermediate frequency coupling 4 to the selective circuit 17.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:—

1. In a radio receiving circuit, an audio amplifier, means for biasing the amplifier beyond plate current cut off, a tuned diode rectifier, said means including a muter stage, an automatic volume control system provided with a signal rectifier which is independent of said diode rectifier, means for impressing the direct current com-

ponent of the diode rectifier current upon said muter stage, the coupling between said muter stage and said audio amplifier being direct and such that when signals are impressed upon said diode rectifier removal of said plate current cut off bias is effected, and said muter stage and rectifier being both provided by a tube provided with a diode section and an amplifier section, said diode section acting as the rectifier and being arranged to have signals impressed thereon, and said amplifier section acting as the muter stage and having an input electrode connected to a point of direct current potential of the diode rectifier.

2. In combination, at least two multiple function tubes, each of said tubes including a diode section and an amplifier section, means for impressing desired signal energy upon the diode section of each of said tubes, each diode section including a tuned circuit for resonating it to the desired signal, the control grid of each of the amplifier sections of said tubes being connected to the diode section of their respective tubes, a resistive coupling between the output electrode of the amplifier section of one of said tubes and the control grid of the amplifier section of the other tube, and an automatic volume control connection to the diode section of said last named other tube.

3. In a radio receiver including a multiple function tube provided with at least one diode section and an amplifier section, a signal input circuit connected to the diode section, an automatic volume control network connected to a resistor in the signal input circuit across which is developed a rectified signal voltage, means between said resistor and the control grid of said amplifier section for impressing the audio component of rectified signal energy upon said amplifier section, a rectifier, a noise control electron discharge device having its input electrodes coupled to the said rectifier, a direct current connection between the anode of said noise control device and the control grid of the amplifier section of said first tube, and a highly selective signal input circuit coupling said first named signal input circuit and said rectifier, said highly selective circuit being relatively loosely coupled to said first signal input circuit.

4. In a radio receiver including a multiple function tube provided with at least one diode section and an amplifier section, a signal input circuit connected to the diode section, an automatic volume control network connected to a resistor in the signal input circuit across which is developed a rectified signal voltage, means between said resistor and the control grid of said amplifier section for impressing the audio component of rectified signal energy upon said amplifier section, a rectifier physically independent of said tube, a noise control electron discharge device having its input electrodes coupled to the said rectifier, a direct current connection between the anode of said noise control device and the control grid of the amplifier section of said first tube, and a highly selective signal input circuit coupling said first named signal input circuit and said rectifier.

5. In a receiver as defined in claim 3, the electrodes of said rectifier and noise control device being disposed within a common tube envelope and including a common emission element.
